UNITED STATES PATENT OFFICE.

HERBERT HOLT, OF ROCKDALE, ENGLAND.

MACHINE FOR WINDING YARNS OR THREADS.

Application filed June 21, 1926. Serial No. 117,557.

This invention of improvements in machines for winding yarns or threads relates to machines for winding yarns or threads into cops or pirns or like bodies on spindles or tubes or bobbins or the like thereon.

The principal object of the invention is the provision of machines for winding yarns or threads into cops or pirns or like bodies on spindles or tubes or bobbins or the like thereon and especially winding heads and devices for use in such machines which enable yarns or threads, especially delicate yarns, to be wound into cops or pirns or like bodies of regular formation and precise dimensions at high speeds with a minimum of rubbing of yarns or threads being wound and without any rubbing of yarn or thread wound on spindles, or tubes or the like, ensure that the windings of yarn or thread in cops or pirns or like bodies shall be securely bound together and held against easily shelling off or unwinding in manipulation or transport of the cops, pirns or like bodies, ensure that spindles or parts on which the winding of yarns or threads is effected shall be revolved with no or little slip or lost motion by the parts from which they receive motion, enable the spindles or parts on which winding of yarns or threads is effected to be stopped quickly when stoppage is requisite as for broken yarns or threads to be pieced and on the completion of cops, pirns or the like, facilitate the work of attendants in piecing broken yarns or threads and placing the knots or piecings where they will not hinder or interfere with the free unwinding of yarn or thread from cops, pirns or like bodies of yarn or thread, removing completed or full cops, pirns or the like from spindles, the restoration or setting of the machines into condition for the commencement of the winding of fresh cops, pirns or the like, the adjustment of the machines for forming cops, pirns or the like of any length and any diameter requisite within the capacity of the machines and of any requisite taper or inclination of the chase or conical portion, obviate or minimize risk of spindles being strained or bent accidentally in the removal of completed or full cops, pirns or the like therefrom or the application of paper tubes, bobbins or other like bodies thereto, enable yarns or threads to be wound under

very approximately uniform tension when wound from bodies of yarn or thread diminishing in diameter in being unwound and are machines cheap in construction.

With this and other objects hereinafter to be made apparent, the invention consists in a machine and mechanisms and devices to be described in detail with reference to the accompanying drawings, comprising winding heads with spindles which are mounted revolubly about horizontal axes in bearings preferably in headstocks severally supported by the machine framework and are provided with friction clutches constituted in part by driven friction members mounted around, in driving connexion with and movable lengthwise of them in one direction by means of springs and in part by driving friction members mounted around the spindles, and in preferred constructions the bearings of the spindles, to receive engagement of the driven members and driven by any appropriate means for revolving them with certainty so that the driven friction members when engaged with the driving friction members shall turn therewith without risk of slipping and turn the spindles in full correspondence with the turning of the driving friction members and comprising the spindles and means for disengaging the clutches and stopping the spindles, thread guides carried to and fro and moved progressively parallel to the axes of the spindles by and upon screws moved axially parallel to the axes of the spindles by means of arms on an oscillating shaft and provided one for each spindle and revolved in action by means of bevel wheels mounted around and in driving connexion with them driven by means of bevel wheels which are movable lengthwise of shafts mounted preferably in the headstocks to receive motion by means of bevel wheels turned by devices permitting adjustment of the rate of turning and are moved into and out of engagement with the bevel wheels on the screws concurrently with the engagement and disengagement of the friction clutches of the spindles with which they co-operate by devices allowing the friction clutches to be engaged and disengaging them so that each spindle and screw can be started and stopped separately from the other like spindles and screws. The inven-

tion provides also in such a machine means enabling one adjustment of reciprocating longitudinal movement and one adjustment of progressive longitudinal movement to serve for a plurality of thread guides, convenient and efficient means for enabling the moving thread guide used with a spindle to bring about with certainty the disengagement of the friction clutch of that spindle and the stoppage of the spindle and of the progressive movement of the thread guide itself when a cop, pirn or the like is completed, stops for enabling the stoppage of winding to be stopped in different positions of the progressive movement of the thread guides to limit the length of the cops, pirns or the like to be formed at different times, stops for facilitating the accurate return of thread guides to the positions for starting the formation of cops, pirns or other bodies and capable of being easily set in position for the formation of cops, pirns or the like of any length requisite, safety stops adjustable upon the thread-guide-carrying screws for enabling the stops for effecting the stoppage of winding on the completion of cops, pirns or other bodies to be adjusted into position to effect stoppage very near the termination of the advance of the screws in their reciprocating movement so as to obviate strain or jamming or breakage of mechanism through excessive movement of the thread guides against the stops for effecting the stoppage of winding on the completion of cops, pirns or the like of the length intended, stop mechanism of simple and advantageous form for stopping the spindles when yarns or threads break or come to an end, thread guides easily moved out of ordinary working position to allow attendants tying or piecing broken or terminated yarns or threads to place the knots or piecings in positions where they will not hinder the free unwinding of yarns or threads from the completed cops, pirns or the like in after use, thread guides of simple form providing easily revoluble parts to minimize rubbing of yarns or threads, a cam presenting a cam track which in each revolution effects a plurality of to and fro movements of the screws and thread guides in different ranges differing in their limits.

The invention comprises further, means for transmitting revolution from the clutches to the spindles ensuring effective transmission and obviating danger of binding in movement, and also for transmitting motion to the screws from the bevel wheels around them obviating danger of binding in movement.

The invention comprises further other details as hereinafter described in reference to the drawings and set forth in the claims following.

This invention is illustrated in the ac-

companying drawings which show a winding machine forming an illustrative embodiment of the invention.

Fig. 1 is a partial transverse section of the winding machine showing part of one spindle and mechanism used therewith but omitting an end frame and the spindles at the other side of the machine from the spindle shown.

Fig. 1^x is an end elevation seen in the same direction as Fig. 1 of a part omitted from the upper part of Fig. 1.

Fig. 2 is a side elevation of part of the machine with omissions corresponding generally to those of Fig. 1 and some further omissions.

Fig. 3 is a plan of the part of the machine shown in Fig. 2 but omitting some parts there shown.

Fig. 4 is a side elevation of one spindle and some parts co-operating with it and shows some parts in transverse section.

Fig. 5 is a plan of the mechanism shown in Fig. 4.

Fig. 6 is an end elevation of the mechanism shown in Figs. 4 and 5 seen from the right hand of those figures.

Fig. 7 shows a development of the cam track of a cam employed in the machine.

In Fig. 2 the arrows I indicate the direction in which the parts shown in Fig. 1 are seen.

The same reference characters are applied to corresponding parts in all the figures.

1 is the framework of the machine provided in the preferred construction to support headstocks 2 for the support of spindles 3 and parts more immediately co-operating therewith.

For simplicity only a single spindle 3 and a single headstock 2 with the parts mounted in and on it are shown in the drawings and indicated at one side of the machine in Fig. 1 but in the machine represented there is a number of spindles 3 at each side of the machine each mounted in a headstock 2 similar and similarly to those shown and in any case in which it may be desirable a machine is constructed to present spindles 3 at only one side. The headstocks 2 are mounted on rails 4 forming part of the framework 1. The headstocks 2 are formed each in two parts 2^x and 2^{xx} secured together and providing respectively bearings 5, 6 at the rear or interior of the machine and nearer the front or exterior of the spindles 3.

For simplicity in description, the one spindle 3 shown and the parts provided more or less exclusively for operation in combination with that spindle 3 or with that spindle and others carried by the same rail 4 will generally be referred to in description. The front bearing 6 of the headstock 2 presents an inwardly extending sleeve 7 around which a driving member 8 formed

in the preferred construction shown with one outwardly conical part 9 forming one part of a cone friction clutch and provided preferably as shown with a pad 10, shown as annular, of frictional material is mounted to revolve. A collar 11 secured as by a set screw 12 on the spindle 3 to bear against the sleeve 7 and a ball thrust bearing 13 provided at the opposite side of the front bearing 6 and comprising a collar secured on the spindle 3, as by a set screw, hold the spindle 3 against axial movement. The collar 11 also holds the driving member 8 on the sleeve 7. The driving member 8 may be revolved by any suitable means but in the case shown a flexible driving tape 14 is employed for revolving it. A driven member 15, shown in the preferred construction illustrated, as formed with an interior cone to co-operate with the conical part 9 of the driving member 8 and constituting the other part of a conical friction clutch, is mounted so that it may be slidden axially of the spindle 3 and is placed in driving connexion with the spindle 3 by being formed with holes through which extend rods 16 extending parallel to the axis of the spindle 3 and secured as by being screwed in the collar 17 secured, as by a set screw 18, on the spindle 3. The collar 17 and rods 16 transmit motion to the spindle 3 without risk of binding. A spring 19 is interposed between the driven member 15 and the collar 17 and holds the driven member 15 in engagement with the driving member 8 so that the spindle 3 is driven without or substantially without slip or lost motion relatively to the driving member 8. The driven member 15 is shown as formed with an external collar 20. In order that the driven member 15 may be disengaged from the driving member 8 and the spindle 3 may be stopped, a forked arm 21 presenting arms on opposite sides of the driven member 15 to be made to bear against the collar 20 is fixed on a shaft 22 mounted to oscillate in the headstock 2 and a spring 23 of sufficient strength to overcome the resistance of the spring 19 and move the arm 21 in a clockwise direction as seen in Fig. 4 is connected with one end to the arm 21 and at the other to an eyed stud 24 in the part 2^{xx}. When the spring 23 is allowed to move the arm 21, the two arms of the forked part act as brakes against the collar 20 and quickly stop the spindle 3. For each tape 14 there is provided a tightening pulley 25 which is mounted between the two sides of the fork of a forked arm 26 secured as by a set screw 27 on a fixed rod 28 extending along the machine for the distance requisite and fixed in brackets 281 on the cross frame 29 forming part of the frame 1 and a similar cross frame at the end of the machine not shown.

The tape 14 for driving the driving member 8 is made to pass around and to receive motion from one of a number of pulleys 30 fast on a shaft 31 mounted in brackets 32 on the frame 29 and the similar frame, not shown, at the other end of the machine and also in the end frame 33 forming part of the framework 1 and connected with the frame 29 by distance pieces 34. The shaft 31 is made to receive revolution in any suitable way and as shown is provided with step pulleys 35 driven by means of a belt 36 by stepped pulleys 37 fast on a shaft 38 mounted in bearing brackets 381, 382 on the frames 29, 33 respectively, provided with fast and loose pulleys 39, 40. On the shaft 31 a sprocket wheel 41 is fixed, which by a chain 42, communicates motion to a sprocket wheel 43 fast on a shaft 44 mounted in the frame 29 and extending also in a bearing in one side of a gear box 45 secured as by set screws to the end frame 33. Within the gear box 45 the shaft 44 has fast upon it a bevel wheel 46 gearing into a bevel wheel 47 fast on a cross shaft 48 mounted in the walls of the box 45. Fast on the shaft 48 within the box 45 is a cam 49 presenting a cam track 50 which has a plurality of pairs of oppositely inclined or directed parts of different extents or extents and limits of range or variation from a mid position for giving movement first one way and then in the opposite direction and of different extents and within different limits to a bowl 51 mounted to revolve on an arm 52 fixed on a shaft 53 mounted to oscillate in the walls of the box 45 and having fast on it outside the box 45 a slotted arm 54 connected to a slotted arm 55 fast on an oscillatable shaft 56 mounted in brackets 561 on the cross frame 29 and the other similar cross frame already mentioned. The slotted arms 54, 55 are connected by a stud 57 fixed in the slot of the arm 54 and made to engage the slot of the arm 55 and adjustable in position towards or away from the axis of oscillation of the arm 54 and enabling the extent of the oscillatory movement of the shaft 56 to be adjusted. Fast upon the shaft 56 is another slotted arm 58 which transmits oscillatory movement to a similar slotted arm 59 on another oscillatory shaft 60 mounted in brackets 601 and corresponding to the shaft 56 carrying the arm 58 but serving for the other side of the machine. The arms 58, 59 are connected by a stud 61 adjustably secured in the slot of the arm 58 and engaging the slot of the arm 59 and by its adjustment nearer to or further from the axis of oscillation of the arm 58 enabling the oscillatory motion of the shaft 60 to be adjusted.

A toothed wheel 62 fast on the shaft 31 is made to drive a toothed wheel 63 fast with a sprocket wheel 64 and made to re-

olve on a stud 65 fixed in the frame 29. The sprocket wheel 64 is made to drive by a chain 66 a sprocket wheel 67 on a shaft 68 mounted in brackets 681 on the frame 29 and the other similar frame mentioned. The sprocket wheel 67 serves to transmit motion to the driving members 8 used with spindles 3 at the right hand side of the machine as seen in Fig. 1 by means of pulleys 10 mounted on the shaft 68 and corresponding to the pulleys 30.

In a projection 2^{xxx} on the part 2^{xx} of the headstock 2 a vertical shaft 69 is mounted to revolve and held against axial movement by 15 means of a collar 70 and a bevel wheel 71 secured upon it by set screws 72.

Around the upper end of the shaft 69 a bevel wheel 73 is mounted to be capable of axial movement and in engagement with a 20 key 74 fixed in the shaft 69 so that the bevel wheel 73 always turns when the shaft 69 is revolved.

The shaft 69 is made to receive an intermittent turning derived from the continuous revolution of the shaft 44. Fast on the shaft 44 is a sprocket wheel 75 made to drive by means of a chain 76 a sprocket wheel 77 fast on a short shaft 78 mounted in a bearing in a bracket 781 on the frame 29 on 25 which shaft 78 a sprocket wheel 79 is mounted. The sprocket wheel 79 is made to drive a chain 80 driving a sprocket wheel 81 on a short shaft 82 mounted in a bearing in a bracket 821 on the frame 29. Fast on the 30 short shaft 82 is a disc 83 to which is secured a slotted cross bar 84 furnished with a crank pin 85 adjustably secured in it as by means of a nut screwed on said crank pin 85. A connecting rod 86 connected to the crank pin 85 is connected to a lever 87 made to oscillate about a short shaft 88 mounted in a bearing in the frame 29 and provided with a ratchet wheel 89 and toothed wheel 90 fast upon it. The lever 87 is provided with a pawl 91 pivoted to it and under the influence of a spring 40 not shown but engaged with the lever 87 and pawl 91 and coiled around the pivot of the pawl 91 and tending to hold the pawl 91 in engagement with the teeth of the ratchet wheel 89. The wheel 90 is formed and provided as a change wheel made to transmit motion through a carrier wheel 92 revoluble on a stud 93 adjustably secured as by a nut in a slotted arm 94 secured as by means of a 45 set screw on a boss on a bracket 95 secured on the frame 29 to a toothed wheel 96 on a shaft 97 at the left hand side of the machine in Fig. 1 and extending along the machine and mounted in the bracket 95 and another bracket on the other similar frame not shown. The sprocket wheel 77 is provided with a slotted cross bar 98 furnished with a crank pin 99 transmitting motion similarly to the crank pin 85 through a connecting rod 86, lever 87, pawl 91, ratchet wheel, 89,

change wheel 90, carrier wheel 92 and toothed wheel 96 to a shaft 97 at the right hand side of the machine in Fig. 1, and corresponding in function to that at the left hand side.

The shaft 97 is provided with bevel wheels 100 which gear with the bevel wheels 71 on the several upright shafts 69, only one of the bevel wheels 100 on the left hand shaft 97 being shown.

The boss of the bevel wheel 73 is formed with a groove engaged by projecting pivots 101 secured in the two branches of a forked arm 102 fixed on the shaft 22 so that when the arm 21 is moved by the spring 23 the bevel wheel 73 is moved downwards. An arm 103 fast on the shaft 22 is provided with a finger plate or handle 104 by which an attendant may overcome the spring 23 and raise the bevel wheel 73 and allow the spring 19 to force the driven member 15 into engagement with the driving member 8. The arm 102 is formed with an arm provided with a catch part or tooth 105 to be engaged with a catch part or tooth 106 on a plate 107 pivoted by means of a stud 108 on a bracket 109 formed on the part 2^x of the headstock 2.

The plate 107 hereinafter further to be described forms a trip device, by which the shaft 22 can be held against movement by the spring 23 acting on the arm 21 and the arm 21 can be held clear of the collar 20 and the bevel wheel 73 can be held raised in the position in which it is shown in the drawing and in gear with a bevel wheel 110 fast with a sleeve 111 capable of revolution but held by a collar 112 fixed upon it, as by a set screw, against axial movement in a bearing provided in the part 2^x of the headstock 2. A screw 113 axially movable is slidably mounted with its axis parallel to that of the spindle 3 in a central hole formed through the bevel wheel 110 and sleeve 111 and is also guided in a guide block 114 secured to a bracket 115 fixed on a rail 116 extending along the machine and fixed in brackets not shown but provided on the frame 29 and the other similar frame mentioned. The bevel wheel 110 is provided with rods 117 fast in it and extending parallel to the screw 113 and made to fit into holes in a collar 118 fixed, as by a set screw 119, to the screw 113 so as to be slid upon the rods 117. The rods 117 and collar 118 enable the bevel wheel 110 to revolve the screw 113 without danger of the occurrence of binding. At one end the screw 113 is provided with collars 120, 121, one of which is fixed upon it as by a set screw, between which collars 120, 121 is a groove entered by dogs 122 pivoted in the two sides of a forked part of an arm 123 fixed on the shaft 56 by set screws 124, which dogs 122 fitting between the collars 120, 121 enable the arm 123 to communicate 110 105 110 115 110 115 120 125 130

a reciprocating axial movement to the screw 113.

5 A guide rod 125 is mounted slidably and parallel to the axis of the spindle 3 and the screw 113 in holes in the part 2^x of the headstock 2 and in the guide block 114 and is held ordinarily in the position in which it is indicated by means of a spring 126 applied around the rod 125 and made to bear 10 at one end against a collar 127 secured thereon and at the other end bearing against a shoulder at the inner end of a hole formed to receive it in the part 2^x at one end of the hole therein guiding the rod 125.

15 The guide rod 125 is provided with a lateral projection 128, in the case shown on a collar 129 fixed upon it as by a set screw 130, which projection 128 extends past a projection 131 on the plate 107 so that if the guide 20 rod 125 is moved in opposition to the force of the spring 126 towards the left hand as seen in Fig. 4, the plate 107 will be tripped and release the arm 105 from movement by the spring 23.

25 An arm 132 shown as of wire and carrying a grooved roller 133 to bear on yarn being wound and ordinarily to be held thereby in the position in which it is shown in Figs. 1 and 4, is pivoted about the stud 108 and movable between two projecting stops 134 and 135 secured in the plate 107. The stop 134 limits the extent to which the arm 132 can be turned counter-clockwise as seen in Fig. 4, about the stud 108 by the 30 yarn being wound and also enables the arm 132 to be used as a handle for moving the plate 107 into position for the catch part 105 to be engaged with the catch part 106. The stop 135 receives contact of the arm 132 35 when it is allowed to fall over clockwise as seen in Fig. 4, by the breakage or ending of yarn being wound and then enables the impact of the arm 132 moving under the influence of its own weight and that of the 40 roller 133 to trip the catch part 106 from the catch part 105 and release the arm 21 for movement by the spring 23.

45 A thread guide carrier 136 made to surround the screw 113 and to engage the guide rod 125, in the case shown by sleeves 137, 138 surrounding the guide rod 125, is provided with a spring pressed dog 139 ordinarily engaging the thread of the screw 113 so as to move forwards and backwards parallel to 50 the axis of the spindle 3 by the axial movement of the screw 113 and gradually forwards parallel to the axis of the spindle 3 by the turning of the screw 113 while being movable towards the part 2^x of the headstock 2 when the dog 139 is disengaged from the threads of the screw 113. A stud 140 is fixed, as by a set screw 141, in a hole in the thread guide carrier 136. The head of the stud 140 is formed as a pivot around which 55 60 65 is turnably mounted a collar 142 radially in

which is screwed an arm 143 of wire. On the arm 143 a grooved roller 1431 to form a thread guide is mounted to revolve and to be movable along the arm 143 between limits determined by collars 1432 and 1433 secured 70 thereon as by set screws. Another wire arm or projection 144 is secured in the collar and bent downwardly to extend down by the side of the head of the stud 140 in order that turning of the collar 142 and arm 143 about the stud 140 may be limited by projecting stops 145, 146 shown as of wire studs mounted in the head of the stud 140. The stops 145, 146 are so placed that when the arm 144 is against the stop 145 the arm 143 extends transversely across and over the spindle 3 and when the arm 144 is against the stops 146, the arm 143 points outwardly away from the spindle 3. Yarn to be wound into a cop, or pirn or similar body around the spindle 3 is led in the case shown from the body from which it is to be unwound over a roller 147 mounted to revolve around a resilient arm 148 carried by a rail 149 supported on standards 150 on the frame 29 and the other similar frame, under the roller 133 and over the thread guide roller 1431 to the spindle or a paper tube or the like thereon. A stop collar 151, in the form of nuts applied one to lock the other, is provided on 80 the screw 113 between the thread guide carrier 136 and the part 2^x of the headstock 2 to form an adjustable stop by which movement of the thread guide carrier 136 towards the part 2^x may be limited to determine the 85 place at which winding of yarn around the spindle 3 shall begin.

90 A stop collar 152 adjustable along the guide rod 125 and when adjusted secured to it, as by a set screw 153, is set upon the guide rod 125 in such a position as to be pushed towards the left hand, as seen in Fig. 4, by the sleeve 137 of the guide carrier 136 when such sleeve 137 in the progressive movement 95 of the thread guide carrier 136 attains a position so as to touch the stop collar 152 just as the screw 113 ends a forward stroke to the left, as seen in Fig. 4, through the oscillation of the arm 123. The thread guide carrier 136 and the stop 152 suitably adjusted along the rod 125 thus enable the winding of yarn around the spindle 3 to be stopped when a cop, pirn or the like of the 100 length intended is completed. Figs. 4 and 5 show the thread guide carrier 136 and guide roller 1431 in a position just short of the stopping place. In order to obviate danger of jamming or breaking of the mechanism through the stop 152 being pushed too early 105 by the sleeve 137 of the thread guide carrier 136 in the advance of the screw 113, a stop collar 154 formed of two nuts made to lock 110 one another is provided on the screw 113 to be set in position thereon to be against the 115 thread guide carrier 136 when the screw 113 120 125 130 is turned.

is fully advanced towards the left hand of Fig. 4, by means of the cam 49 and arm 123 and the dog 139 is engaged with the thread of the screw 113 and the thread guide carrier 136 presents the thread guide 1431 at the position corresponding to the tip of a completed cop, pирн or the like of the length intended and then the stop collar 152 is set just within range of the sleeve 137 of the thread guide carrier 136. Care being obviously needed in the setting of the stop collar 154, error in the subsequent setting of the stop 152 is made improbable.

In the case shown the spindle 3 is provided with a collar 155 secured on it by a set screw 156 to form a stop to determine the position of a paper tube or the like applied to the spindle to receive yarn.

Yarn may be led to the roller 147 and thence to the spindle 3 from any body from which it is to be unwound. In the case illustrated, the yarn is shown as being unwound from a bobbin or other body applied around a creel peg 157 provided with barrel like springs 158 for holding the bobbin or other such body firmly in position, which peg 157 is adapted to be revolved in a suitable support. In the case shown in order that yarn may be unwound without the tension under which it is wound on the spindle 3 varying or varying unduly through the gradual diminution of the diameter of the body of yarn from which it is unwound requiring a greater tension on the yarn to effect unwinding against any drag or resistance applied to prevent the bobbin from which yarn is being unwound from over-running and letting slack the yarn or turning unsteadily, the creel peg 157 which is provided with a collar or brake drum 159 to receive application of a brake is mounted to be revolved in notches 160 formed in the arms of a cradle or forked bracket 161 which, being mounted to be oscillated about a rod 162 supported by the standards 150, is provided with an arm 163 weighted to counterbalance a proportion of the weight of the arms of the cradle 161 and the peg 157 and body of yarn thereon, in the case shown by means of a weight 164 adjustable upon it and secured by means of a set screw, and acting as a counterpoise counterbalancing a greater or less proportion of the weight of the cradle 161, peg 157 and body of yarn as it is fixed on the arm 163 nearer to or further from the rod 162. A bracket 165 is fixed on the rod 162, as by a set screw, and in this bracket 165 is fixed, as by a set screw 166, a rod 167 bearing a pivot stud or projection 168 on which is applied a bow frame 169, shown as a resilient fork of wire, presenting a loop to grasp and to hold the bow frame 169 upon the pivot stud 168. To the two arms of the bow frame 169 a brake-band 170 of frictional material, for example leather, is

secured by means of nuts 171 secured upon the arms and the bow frame 169 is adjusted in position for the collar or brake drum 159 of the peg 157 to bear upon it. The one arm of the bow frame 169 is curved in part so as not to obstruct the collar or brake drum 159 of the peg 157 when the cradle 161 is raised or turned in the removal or the application of the peg 157 therefrom or therefo. The collar or brake drum 159 bears most heavily on the brake band 170 when the bobbin or body of yarn on the peg 157 is full and gradually more lightly as the body of yarn around the peg diminishes in quantity and diameter so that the tension needed to be applied on the yarn to revolve the peg 157 and body of yarn decreases in more or less approximate correspondence with the diminution of the diameter of the body of yarn and the winding of yarn on the spindle 3 is effected under more or less approximately uniform tension.

In preparation for the commencement of winding of a cop or pирн or the like on a spindle 3 of the machine, the dog 139 of the thread guide carrier 136 being disengaged from the thread of the screw 113, the thread guide carrier 136 is easily pushed back against the stop collar 151 for the commencement of a cop, pирн or the like and the yarn being led to the spindle 3, pressure on the finger plate 104 and movement of the arm 132 to raise the roller 133, by a person working with the machine, enable the catch part 106 to be engaged with the catch part 105 and the bevel wheel 73 to be engaged and held in engagement with the bevel wheel 110 and the spring 19 being freed from the resistance of the spring 23 is enabled to press the driven member 15 into and to hold it firmly in engagement with the driving member 8 so that the spindle 3 shall be revolved with the driving member 8 and without risk or appreciable risk of slipping or lost motion until the formation of a cop, or pирн or other like body around the spindle 3, either on the spindle 3 itself or a paper tube or other body thereon as may be requisite from time to time, is completed or until the yarn being wound breaks or comes to an end. So long as the spindle 3 is revolved the screw 113 continues to be reciprocated forwards and backwards by the cam 49 and being turned intermittently to impart through the dog 139 in engagement with its thread, a progressive movement to the thread guide carrier 136 and thread guide 1431 and through the cam track 50 of the cam 49 presenting a plurality of pairs of sections of opposite hand of different extent, gives to the screw 113 successive forward and backward traverses within different limits and so causes some of the successive coils of yarn wound one over another to overlap and others to fall short of the ends of the coils

or windings wound immediately before them, sometimes at one end and sometimes at the other, so that the coils or windings forming the successive taper layers or windings of a cop, pirn or like body are very firmly bound together so as to be held firmly against shelling off or unwinding by their own weight, as slippery yarns, such as those of artificial silk, are liable to do unless very firmly bound. The yarn being wound receives little friction in being unwound from the body or form in which it may be prepared for supply to the spindle since on the way thereto it is guided by rollers freely revolving and so not liable to rub it so as to cause injury to any yarn however delicate and when once wound around the spindle it receives no further rubbing. As soon as the sleeve 137 of the thread guide carrier 136 touches and pushes the stop 152, the catch part 105 is released and the spring 23 causes the driven member 15 to be disengaged from the driving member 8 and stopped quickly by the braking action of the forked arm 21 and also disengages the bevel wheel 73 from the bevel wheel 110 which then stops so that, although the screw 113 continues to reciprocate, the progressive movement of the thread guide carrier 136 and thread guide 1431 stops. Similarly if the yarn being wound break or terminate, the roller 133 and arm 132 will fall to the right hand as seen in Fig. 4, and the arm 132 striking the stop 135 will trip the catch 106 and the spindle 3 and bevel wheel 110 will be stopped quickly. When the broken or terminated yarn has been pieced or connected to the yarn from another body to be unwound and used to supply yarn to the spindle 3, the attendant working with the machine can move the arm 143 carrying the thread guide 1431 into a position away from the spindle 3 where it no longer obstructs free access to the already wound part of a cop, pirn or other body and so is enabled easily to coil the yarn thereon so as to place the knot or piecing behind the tapering part or chase of the cop, pirn or the like where it will not hinder the free unwinding of yarn from such cop, pirn or the like.

It will be obvious that the reciprocating movement of the screw 113 and its turning will cause the yarn to be wound first in cylindrical or nearly cylindrical layers or coils and gradually builds up a conical formation or chase.

It will be seen that the adjustment of the stops provided for co-operation with or actuation by the thread guide carrier 136 provides for easy adjustment of a head of the machine to form a cop, pirn or the like of any length within the capacity of the mechanism and that the adjustment of one or both of the studs 57, 61 adjusting the extent of movement of one or both of the arms

123 and the extent of reciprocation of the screw 113 of each head of the machine at one side or both sides of the machine shown and the adjustment of one or both of the crank pins 85 and 99 adjusting the movement of one or both of the pawls 91 and also the change wheels 90 and 96 used with one or both of the shafts 97, adjusting the rate of turning of the screws 113 at one or both of the sides of the machine enable changes easily to be effected in the diameter and the inclination of the tapering portions or chases of cops, pirns or the like to be wound.

Other advantages of the invention will be apparent from the foregoing description and the drawings.

It will be seen that variation in detail may be made in carrying this invention into effect within the scope of the appended claims.

What I do claim as my invention and desire to secure by Letters Patent is:

1. A yarn winding machine having a framework with bearings for shafts and comprising bearing devices for supporting spindles to revolve therein about horizontal axes, spindles mounted to revolve in said bearing devices and each bearing a place of application for one end of a spring, driving members mounted revolubly around said spindles and each forming part of a friction clutch for imparting revolution to the spindle around which it is applied, means for revolving said driving members, driven members mounted around and movable lengthwise of and in driving connexion with the spindles respectively and each forming another part of the friction clutch for imparting revolution to the spindle around which it is applied, springs applied at one end respectively to said driven members and to the places of application provided for them on said spindles at the other end for forcing said driven members into frictional engagement with said driving members, a shaft to oscillate in said framework, means for oscillating said shaft, arms fast on said shaft, revolute screws movable axially parallel to the axes of said spindles, means for connecting said screws and said arms, bevel wheels mounted around and in driving connexion with said screws, bevel wheels severally movable axially for engagement with and disengagement from the bevel wheels around the screws, means for intermittently turning said axially movable bevel wheels, disengaging means in engagement with said driven members and movable severally in one direction for moving said driven members severally out of engagement with said driving members and having connected means whereby they may be moved severally in the opposite direction to allow said driven members to be engaged with said driving

members, catch parts in connexion with said disengaging means, springs severally engaged with said disengaging means for moving them in one direction and disengaging said driven members from said driving members, means for moving said axially movable bevel wheels into and out of engagement with the bevel wheels around the screws, means provided severally for each 10 spindle for connecting the disengaging means and the means for moving axially the axially movable bevel wheel used with that spindle, holding catches severally movable into position for holding and into position 15 for releasing said catch parts, tripping devices for actuation by thread guide carriers and severally in connexion with said holding catches for moving them and releasing said catch parts, guide rods mounted parallel to said screws, thread guide carriers each with a part for actuating a tripping device and surrounding a screw and engaging a guide rod, thread guides carried by said thread guide carriers and spring pressed 20 dogs in said thread guide carriers severally engageable with and disengageable from said screws.

2. A yarn winding machine as claimed in the preceding claim 1, characterized by each 30 driving member having an outwardly conical part forming part of a cone friction clutch and the co-operating driven member formed with an internally conical part forming the other part of the cone friction clutch.

3. A yarn winding machine as claimed in the preceding claim 1, characterized by each driving member having an outwardly conical part with a pad of frictional material and forming part of a cone friction clutch and 40 the co-operating driven member formed with an internally conical part forming the other part of the cone friction clutch.

4. A yarn winding machine as claimed in the preceding claim 1, characterized by headstocks each of which provides bearings for 45 one spindle and the screw and the shaft holding the axially movable bevel wheel used therewith and other parts serving exclusively for co-operation with said spindle.

5. A yarn winding machine as claimed in the preceding claim 1, characterized by shafts each carrying the disengaging means in engagement with the driven member and the means for moving axially the axially 55 movable bevel wheel used with one spindle.

6. A yarn winding machine as claimed in the preceding claim 1, characterized by shafts holding the axially movable bevel wheels and having bevel wheels fast on them, 60 a shaft having bevel wheels in engagement with the bevel wheels fast on said shafts and means for turning said shaft.

7. A yarn winding machine as claimed in the preceding claim 1, characterized by 65 shafts holding the axially movable bevel

wheels and having bevel wheels fast on them, a shaft having bevel wheels in engagement with the bevel wheels fast on said shafts, means comprising a pawl and ratchet wheel for turning said shaft and means for adjusting the movement imparted by the pawl to the ratchet wheel. 70

8. A yarn winding machine as claimed in the preceding claim 1, characterized by shafts holding the axially movable bevel wheels and having bevel wheels fast on them, a shaft having bevel wheels in engagement with the bevel wheels fast on said shafts, means comprising a pawl and ratchet wheel for turning said shaft and change gearing 75 for adjusting the turning of the said shaft and axially movable bevel wheels in relation to the turning of the ratchet wheel.

9. A yarn winding machine as claimed in the preceding claim 1, characterized by shafts holding the axially movable bevel wheels and having bevel wheels fast on them, a shaft having bevel wheels in engagement with the bevel wheels fast on said shafts, means comprising a pawl and ratchet wheel 80 for turning said shaft, means for adjusting the movement imparted by the pawl to the ratchet wheel and change gearing for adjusting the turning of the said shaft and axially movable bevel wheels in relation to the turning of the ratchet wheel. 85

10. A yarn winding machine as claimed in the preceding claim 1, characterized by stops adjustably fixed on the screws between the thread guide carriers and the bearings adjacent to the bevel wheels surrounding 90 the screws. 100

11. A yarn winding machine as claimed in the preceding claim 1, characterized by guide rods, which are movable lengthwise 105 in the supports of the spindles and parallel to the axes of the several spindles and axially movable screws, receive engagement of the thread guide carriers of the several spindles and are provided with lateral projections and with parts to receive application of springs, springs applied to said parts and to the supports of the spindles for resisting movement of said guide rods in one direction, thread guide carriers respectively engaging said guide rods and each presenting, 110 adjacent to the guide rod engaged by it, a contact part to be brought against a collar on said guide rod, collars which are provided on said guide rods to be actuated by the contact parts of the respectively co-operating thread guide carriers and adjustable lengthwise of said guide rods, means for securing said collars when adjusted on said guide rods respectively and levers which are respectively mounted for oscillation on parts of the supports of said spindles and are severally provided with parts to be engaged by the lateral projections on said guide rods respectively and also severally provided with catch 115

parts for engagement with and disengagement from the means for disengaging the driven members from the driving members and the means for moving axially the axially movable bevel wheels whereby said guide rods being moved by said thread guide carriers respectively will move the co-operating levers with catch parts and disengage the co-operating driven members from the 10 driving members used with them and the axially movable bevel wheels from those around the screws co-operating with said guide rods.

12. A yarn winding machine as claimed in the preceding claim 1, characterized by guide rods which are movable lengthwise in the supports of the spindles and parallel to the axes of the several spindles and axially movable screws, receive engagement of the thread 20 guide carriers of the several spindles and are provided with lateral projections and with parts to receive application of springs, springs applied to said parts and to the supports of the spindles for resisting movement 25 of said guide rods in one direction, thread guide carriers respectively engaging said guide rods and each presenting, adjacent to the guide rod engaged by it, a contact part to be brought against a collar on said guide 30 rod, collars which are provided on said guide rods to be actuated by the contact parts of the respectively co-operating thread guide carriers and adjustable lengthwise of said guide rods, means for securing said collars 35 when adjusted on said guide rods respectively and levers which are respectively mounted for oscillation on parts of the supports of said spindles and are severally provided with parts to be engaged by the lateral 40 projections on said guide rods respectively and also severally provided with catch parts for engagement with and disengagement from the means for disengaging the driven members from the driving members and the 45 means for moving axially the axially movable bevel wheels whereby said guide rods being moved by said thread guide carriers respectively will move the co-operating levers with catch parts and disengage the 50 co-operating driven members from the driving members used with them and the axially movable bevel wheels from those around the screws co-operating with said guide rods and further characterized by stop collars adjust- 55 able on the axially movable screws between the thread guide carriers and the ends most remote from the bevel wheels surrounding such screws.

13. A yarn winding machine as claimed in the preceding claim 1, characterized by levers which are respectively mounted for oscillation on parts of the supports of the spindles and severally provided with catch parts for engagement from the means for 60 disengaging the driven members from the

driving members and the means for moving axially the axially movable bevel wheels, and are provided with pivots for roller carrying levers and stops for limiting movement of said roller carrying levers about the pivots, 70 roller carrying levers mounted about the said pivots and between said stops and rollers mounted on said roller carrying levers to be supported by yarns being wound while intact and released when said yarns break 75 or end.

14. A yarn winding machine as claimed in the preceding claim 1, characterized by guide rods, which are movable lengthwise in the supports of the spindles and parallel to the axes of the several spindles and axially movable screws, receive engagement of the thread guide carriers of the several spindles and are provided with lateral projections and with parts to receive application of springs, springs applied to said parts and to the supports of the spindles for resisting movement of said guide rods in one direction, thread guide carriers respectively engaging said guide rods and each presenting, adjacent to the guide rod engaged by it, a contact part to be brought against a collar on said guide rod, collars which are provided on said guide rods to be actuated by the contact parts of the respectively co-operating thread guide carriers and adjustable lengthwise of said guide rods, means for securing said collars when adjusted on said guide rods respectively and levers which are respectively mounted for oscillation on parts of the supports of said spindles and are severally provided with parts to be engaged by the lateral projections on said guide rods respectively and provided further with 90 pivots for roller carrying levers and stops for limiting movement of said roller carrying levers about the pivots and also severally provided with catch parts for engagement with and disengagement from the means for disengaging driven members from the driving members and the means for moving axially the axially movable bevel wheels, roller carrying levers mounted about the said pivots and between said stops on said levers with catch parts, rollers mounted on said roller carrying levers to be supported by yarns being wound while intact and released when said yarns break or end, whereby said guide rods being moved by said thread guide carriers respectively or release of said rollers will move the co-operating levers with catch parts and disengage the co-operating driven members from the driving members used with them and the axially movable bevel wheels from those around the screws co-operating with said guide rods.

15. A yarn winding machine as claimed in the preceding claim 1, characterized by guide rods, which are movable lengthwise in the supports of the spindles and parallel to

the axes of the several spindles and axially movable screws, receive engagement of the thread guide carriers of the several spindles and are provided with lateral projections and with parts to receive application of springs, springs applied to said parts and to the supports of the spindles for resisting movement of said guide rods in one direction, thread guide carriers respectively engaging said guide rods and each presenting, adjacent to the guide rod engaged by it, a contact part to be brought against a collar on said guide rod, collars which are provided on said guide rods to be actuated by the contact parts of the respectively co-operating thread guide carriers and adjustable lengthwise of said guide rods, means for securing said collars when adjusted on said guide rods respectively and levers which are respectively mounted for oscillation on parts of the supports of said spindles and are severally provided with parts to be engaged by the lateral projections on said guide rods respectively and provided further with pivots for roller carrying levers and stops for limiting movement of said roller carrying levers about the pivots and also severally provided with catch parts for engagement with and disengagement from the means for disengaging driven members from the driving members and the means for moving axially the axially movable bevel wheels, roller carrying levers mounted about the said pivots and between said stops on said levers with catch parts, rollers mounted on said roller carrying levers to be supported by yarns being wound while intact and released when said yarns break or end, whereby said guide rods being moved by said thread guide carriers respectively or release of said rollers will move the co-operating levers with catch parts and disengage the co-operating driven members from the driving members used with them and the axially movable bevel wheels from those around the screws co-operating with said guide rods and further characterized by stop collars adjustable on the axially movable screws between the thread guide carriers and the ends most remote from the bevel wheels surrounding such screws.

16. A yarn winding machine as claimed in the preceding claim 1, characterized by the spindles being provided with collars which are fast upon them and are provided

with rods fast in them and the driven members having holes to receive such rods.

17. A yarn winding machine as claimed in the preceding claim 1, characterized by collars severally secured on the screws and provided with holes and the bevel wheels mounted around the screws having rods passing through the holes of said collars.

18. A yarn winding machine as claimed in the preceding claim 1, characterized by arms severally pivoted and capable of being turned into and out of ordinary position relatively to the thread guide carriers and bearing thread guides and by the thread guide carriers having stops for limiting movement of said arms and the thread guides thereon about their axes of turning in movement from and return to their ordinary position relatively to the thread guide carriers.

19. A yarn winding machine as claimed in the preceding claim 1, characterized by arms severally pivoted and capable of being turned into and out of position relatively to the thread guide carriers and providing axles for supporting rollers forming thread guides and by the thread guide carriers having stops for limiting movement of the said arms and the rollers forming thread guides about their axes of turning in movement from and return to their ordinary position relatively to the thread guide carriers.

20. A yarn winding machine as claimed in the preceding claim 1, characterized by means for adjusting the extent of oscillation of the oscillatable shaft.

21. A yarn winding machine as claimed in the preceding claim 1, characterized by a cam which, serving for oscillating the shaft to oscillate in the framework, is provided with a cam track presenting a plurality of pairs of oppositely directed track portions with different limits of range.

22. A yarn winding machine as claimed in the preceding claim 1, characterized by a cam which, serving for oscillating the shaft to oscillate in the framework, is provided with a cam track presenting a plurality of pairs of oppositely directed track portions with different extents and limits of range.

In testimony, that I claim the foregoing as my invention, I have signed my name this tenth day of June, 1926.

HERBERT HOLT.
